Albert Rush
his Attorney

UNITED STATES PATENT OFFICE

ALBERT RUSH, OF COLUMBUS, OHIO, ASSIGNOR TO THE KINNEAR MANUFACTURING COMPANY, OF COLUMBUS, OHIO, A CORPORATION OF OHIO

DOOR FOR HANGARS AND OTHER STRUCTURES

Original application filed November 12, 1927, Serial No. 232,775. Divided and this application filed October 25, 1929, Serial No. 402,518.

Owing to the horizontal spread of the planes or wings of a flying machine or the enormous size of a dirigible balloon a hangar or other housing for such a device must have a very wide entrance, and because of such width it does not appear to be economically practical to provide such an entrance with a single rolling steel door. A steel rolling door should have vertical guiding and retaining channels for its edges, hence if a plurality of doors is to be provided for the entrance of a hangar there is presented the problem of displacing such guiding channels or posts containing one or more of them when the entrance is to be opened. The present invention, therefore, has for its principal object improved means for operating such doors. The invention also has other objects as will hereinafter appear and as may be collateral to the principal object.

The invention is embodied in the example herein shown and described, the features of novelty being finally claimed.

In the accompanying drawing—

Figure 1 is a view in elevation of the entrance and of a hangar equipped with the invention.

Fig. 2 is a combined vertical section and elevation, broken out horizontally and looking toward the channel-side, of one of the posts with means for electrically operating the door.

Fig. 3 is a front view of the post as constructed in Fig. 2.

Fig. 4 is a detail edge view of the post showing the circuit extending means removed.

Fig. 5 is a similar view showing the circuit extending means applied.

Fig. 6 is an end elevation of the circuit extending means looking to the right as seen in Fig. 5.

In the views the character 15 designates the building with the entrance thereto at 16. Installed upon the front wall above the entrance is a plurality of flexible steel rolling doors 70 covered with hoods 17, 17^a and 17^b, the rolling doors being of the usual construction with winding shafts 12 and end brackets 13. These rolling doors are preferably coun-

terbalanced, as usual in that type, so that each of them can be easily unrolled and rolled up and remain in rolled up condition when the means for performing these operations is removed.

Mounted on the wall of the building above the hoods of the rolling doors are suitable brackets 18, to the lower faces of which are secured strips 19 provided with car trolley tracks 20, 20, extending parallel to the tops of the hoods. 21 designates a stout frame of reversed C-form, roughly, as viewed in Fig. 2, to the lower arm of which is secured a post 23 having curtain guiding and retaining channels 24 at its opposite vertical sides to receive and guide the adjacent edges and margins of two of the doors, or curtains. Only the intermediate posts require two door guiding channels and only one of the end or stationary corner posts requires curtain operating means. The upper arm of the frame 21 is equipped with suitable trolleys 25 that engage the tracks 20, 20, said tracks and trolleys supporting the frame 21, the post 23 and the parts attached thereto, and permitting the horizontal movement of said parts across the entrance of the building.

In Fig. 1 one of the doors is shown as closed, with one of the intermediate posts in position to permit operation of the rolling door.

In the present instance the power used to wind and unwind the curtain is electrical and the curtain roller is shown as provided with a large bevel gear 50 engaged by a bevel pinion 51 fixed to the outer end of the shaft 52 of an ordinary electric motor 53 supported on a suitable bracket 54 secured to the inner side of the wall. The electric circuit for the motor 53 includes wires 55 that terminate in suitable fixed contacts 56 in a suitable frame 57 secured to the lintel of the doorway. The circuit connecting device is carried on the inner end of a lever 58 that extends through the post 23 and is fulcrumed on a bracket 59. The circuit connecting device has a plate 60 for carrying spring supported contacts 60^a to close with the contacts 56, and its position for connecting and extending the circuits is controlled manually by a chain 61 that passes through a flexing member 62 and 100

a chain detaining device at 63 to hold the circuit closer up in circuit extending position when the electric motor is to be operated. When the post is to be moved horizontally 5 after the curtain has been raised the chain 61 is removed from the detaining device at 63 and the closer allowed to drop by gravity from its circuit extending position and so left until the post is to be replaced for the 10 closing of the curtain or door at which time the plate 60 is again raised by drawing down the chain 61 and latching it as before described. The wires from the plate 60 are extended through a tube 64 on the front of 15 the post to a box containing three spring push buttons, 65, 65^a and 65^b for the purpose of operating the motor in direct or reverse to raise or lower the curtain and to stop the motor and curtain at any point desired. The 20 plate 60 is provided with a wedge-shaped guiding portion 66 that enters a socket in the base of the structure carrying the contacts 56.

While I have shown and described the invention as applied to buildings for receiving aerial vehicles it will be understood that the invention can be used in connection with any structure where it is desirable to close a wide opening or to remove a channel carrying post.

30 The forms of the parts can be changed without departing from the gist of the invention as claimed.

The present application is a division of an application filed by me November 12, 1927, 35 Serial number 232,775.

What I claim is:

1. In combination with a structure provided with a plurality of doors or curtains, a post having a guide for a margin on one 40 of said curtains, means for supporting said post permitting it to be slid laterally into and out of margin-guiding position, electrically operated power means for operating said doors or curtains and means carried by 45 the post for causing the operation of said power means.

2. In combination with a structure provided with a plurality of doors or curtains, a post having a guide for a margin of one 50 of said curtains, means for supporting said post permitting it to be slid laterally into and out of margin-guiding position, electrically operated means for raising and lowering said curtain, and means on the post for 55 controlling said electrically operated means.

3. In combination with a structure provided with a plurality of doors or curtains, a post having a guide for a margin of one of said curtains, means for supporting said 60 post permitting it to be slid laterally into and out of margin-guiding position, electrically operated means for raising and lowering said curtain, removable circuit sections extending from said electrically operated 65 means connected with the post and means on

the post for controlling said electrically operated means through said circuit sections.

4. In combination with a structure provided with a plurality of doors or curtains, a post having a guide for a margin on one 70 of said curtains, means for supporting said post permitting it to be slid laterally into and out of margin guiding position, stationarily mounted electrically operated power means for raising and lowering said curtains, and means carried by the post for causing the 75 operation of said electrically operated power means.

5. In combination with a structure provided with a plurality of doors or curtains, a post having a guide for a margin of one 80 of said curtains, means for supporting said post permitting it to be slid laterally into and out of margin guiding position, stationarily mounted electrically operated power 85 means for raising and lowering said curtains, and means consisting of a circuit closer and breaker carried by the post for causing the operation of said electrically operated power means.

6. In combination with a structure provided with a plurality of doors or curtains, a post having a guide for a margin on one of said curtains, means for supporting said post permitting it to be slid laterally into and out of margin guiding position, stationarily mounted electrically operated power means for raising and lowering said curtains, and means consisting of a hinged circuit closer 95 and breaker carried by the post for causing the operation of said electrically operated power means.

ALBERT RUSH.
